FUEL-OIL ATOMIZER.

1,188,754.

Specification of Letters Patent.

Patented June 27, 1916.

Application filed June 28, 1915. Serial No. 36,835.

To all whom it may concern:

Be it known that we, PAUL L. GEER and GEORGE E. Woods, citizens of the United States, and residents of San Jose, in the county of Santa Clara and State of California, have invented a certain new and useful Improvement in Fuel-Oil Atomizers, of which the following is a specification.

Our invention relates to an improvement in fuel oil atomizers, and the objects of our invention are: First to produce a fuel oil atomizer that can be permanently attached to the inside of a fuel oil tank, and one that will produce a combustible vapor without heating said fuel oil. Second, to so construct a fuel oil atomizer whereby the air pressure required will be equal to the pressure required upon the fuel oil. Third, to so construct a fuel oil atomizer that will produce any required richness of vapor under the same pressure. Fourth, to so construct a fuel oil atomizer that will produce a vapor by adjustment equal to the heat or work required of the same. We accomplish these objects by means of the atomizer illustrated in the accompanying drawings, in which:—The figure is a detail sectional view showing means of attaching the atomizer to the inside of an oil fuel tank with air feed pipes and oil feed pipes in position, parts broken away.

In the accompanying drawings similar reference numerals refer to similar parts.

Referring now to the drawing, our improved fuel oil atomizer consists of a fuel oil and air tank combined as 1; this tank may be made of any suitable metal required and of any size desirable and of the proper thickness to retain the pressure required to operate said atomizer. A top plate of extra thickness is shown at 2. This top plate is fastened to tank 1 in any suitable manner, having a hole 3 bored through said plate of the required size and threaded 10 to receive vapor chamber 4. We have here shown vapor chamber 4 in globe shape. We do not wish to confine ourselves to this particular shape, as the same may be made straight, having threads cut on the outside thereof at 5, adapted to screw into plate 2 at 3; at the top of said vapor chamber 4 is shown atomized oil outlet 6. This outlet may be connected to an oil burner or to any other suitable connection where the 55 atomized vapor may be required. The lower

end of said vapor chamber 4 having threads 7 cut on the inside thereof is adapted to engage atomizer nozzle 8 by threads cut on the outside thereof at 9, the upper end of said nozzle 8 being made convex as 60 shown at 10, having a plurality of slots 11 cut therethrough for the purpose of more thoroughly vaporizing the mixture passing therethrough. On the inside of said atomizer nozzle 8, and an integral part thereof, 65 are a plurality of baffle plates 12; these assist greatly in vaporizing the mixture as the same passes therethrough under pressure. At the lower end of said atomizer nozzle 8 is connected pipe tube 13. At the 70 top of said tube, and an integral part thereof, is distributing plate 14, said plate having a plurality of holes 15 bored therethrough of the required size for the purpose of delivering the mixture of air and 75 oil under pressure therethrough to baffle plates 12; connected to plate 14 is pipe 16, having its opening 16^a through said distributing plate 14; this pipe opening is for the purpose of quickly increasing the mixture to baffle plates 12 when so required; 80 tube 13 and pipe 16 are here shown connected to cap 17 at the lower ends thereof, said pipe 16 having a plurality of oil discharge holes 16^b, through which oil is delivered under pressure to tube 13; oil pipe 85 connections 18 are shown connecting with cap 17 and to controlling valve 19; this valve is for the purpose of controlling the oil supply to pipe 16; a valve stem 20 is shown 90 connecting said valve 19 with the outside control 21 through stuffing box 22 in plate 2; this stuffing box is for the purpose of preventing any leakage around said valve stem 20 when the air pressure is applied 95 to tank 1. At the lower end of said valve 19 is shown the foraminous portion of strainer 23 which is for the purpose of restraining the oil therethrough while entering valve 19 under pressure. Pressure air 100 valve is shown at 24, having a valve stem 25 connecting through plate 2 by stuffing box 26 to the outside control 27; connected to the under side of said air valve 24 is pipe 28, said pipe leading down and connecting with cap 17, through which air is admitted under pressure to tube 13; air supply pipe is shown at 29, connected to plate 2 and opening into tank 1; the same may be connected to any means for supplying 110

pressed air to said tank 1. Pressure gage is shown at 30; this gage is for the purpose of ascertaining the air pressure in tank 1 at all times. A hole 31 of the required size is bored through plate 2 for the purpose of injecting oil therethrough, the same being closed by plug 32. Valve 33 in side of tank 1 is for the purpose of ascertaining the oil level 34 in said tank 1. The operation of our fuel oil atomizer is follows: Oil is admitted to tank 1 through opening 31 by removing plug 32; when tank 1 is filled up to 34 which is ascertained by valve 33, air is admitted to tank 1 through air supply pipe 29 to the required pressure shown by gage 30; air is controlled through valve 24 by outside control 27 to valve 13; oil is admitted to pipe 16 through valve 19, the same being operated by control 21 on the outside of plate 2; by the manipulation of said valves any required mixture of oil and air vapor may be produced in vapor chamber 4, and delivered therefrom through outlet 6, for any purpose required. Having thus described our invention, what I claim as new and desire to secure by Letters Patent, is:—

1. In a fuel oil atomizer of the character described, a fuel oil and air tank combined, an open plate inclosing said oil and air tank, a vapor chamber attached to said plate, a vapor outlet leading from said vapor chamber, an atomizer nozzle attached to said vapor chamber, the upper end thereof being convex; a plurality of slots cut through said convex portion, a plurality of baffle plates attached to the inside of said atomizer nozzle, a connecting tube at the lower end of said atomizer nozzle, a distributing plate attached to the top of said tube having a plurality of holes bored therethrough, a pipe attached to said plate having its opening through said distributing plate, said pipe having a plurality of oil discharge holes therein, a cap which said tube and said pipe are connected, means by which oil is supplied to said pipe and said tube, means by which air is supplied to said cap and said tube, substantially as shown and described.

2. In a fuel oil atomizer of the character described, a fuel oil and air tank combined, an open plate, a vapor chamber, a vapor outlet,

an atomizer nozzle having its upper end convexed, a plurality of slots cut through said convex portion, said nozzle having a plurality of baffle plates inside thereof; a connecting tube, a distributing plate having a plurality of holes bored therethrough, a pipe attached to said plate having its opening through said plate, a plurality of holes in said pipe, a cap to which said tube and said pipe are connected, means by which air is supplied to said cap, oil feed pipe and controlling valve connected to said cap, a valve stem, a stuffing box, means by which said controlling valve is operated, as shown and described.

3. In a fuel oil atomizer, the combination of a fuel oil and air tank combined, a top plate, a vapor chamber, a vapor outlet, an atomizer nozzle having its upper end convexed, a plurality of slots cut through said convex portion, said nozzle having a plurality of baffle plates inside thereof; a connecting tube connected to said nozzle, a distributing plate having a plurality of holes bored therethrough, a pipe attached to said plate having its opening through said plate, a plurality of holes in said pipe, a cap to which said tube and said pipe are connected, oil feed pipe and controlling valve connected to said cap, means for operating said valve, a strainer attached to said valve, a valve stem, a stuffing box, a pressure air valve, a valve stem connecting said valve through a stuffing box to a controlling means outside of said tank, an air pipe connecting with said cap through which air is admitted under pressure to said tube, a supply pipe to admit air to said tank under pressure, a pressure gage attached to the outside of said tank having connection with the inside of said tank, means for injecting oil into said tank, means for ascertaining the oil level in said tank, substantially as shown and described.

In testimony whereof we have hereunto affixed our signatures in presence of two subscribing witnesses.

PAUL L. GEER.
GEORGE E. WOODS.
